(57) **CLAIM**

The ornamental design for a intravitreal injection device, as shown and described.

DESCRIPTION

FIG. 1 is a first perspective view of a intravitreal injection device according to my new design.

FIG. 2 is a second perspective view thereof.

FIG. 3 is a front elevational view thereof.

FIG. 4 is a rear elevational view thereof.

FIG. 5 is a top plan view thereof.

FIG. 6 is a bottom plan view thereof.

FIG. 7 is a left side elevational view thereof, enlarged to show details of the design.

FIG. 8 is a partial view of FIG. 2, showing a contact head at the left end of the intravitreal injection device, enlarged for magnification purposes; and,

FIG. 9 is a partial, enlarged view of the underside of the contact head as shown in FIG. 8.

The broken lines in FIGS. 8 and 9 indicate boundary lines of the areas being enlarged.
